FEEDBACK CIRCUIT AND RADIO RECEIVER

Rodney F. Pratt, Grahamsville, N. Y., assignor of one-half to Manuel Dittenheimer, Ellenville, N. Y.

Application July 21, 1938, Serial No. 220,547

3 Claims. (Cl. 179—171)

My invention relates to improvements in radio receiving and amplifying systems and the like and has for its objects increasing the amplification and effectiveness of the vacuum tubes employed together with improvement in tone quality obtained and the reduction of electric current required resulting in unusual economy of operation.

In the drawing, Figure 1, is shown as a three tube radio receiving circuit suitable for the application of the principles of my invention wherein the circuit elements selected are of unusual values giving unusual operating conditions and thereby producing new and improved results; and, Figure 2, there is shown a diagrammatic equivalent circuit illustrating the principles of operation employed in my invention.

Referring to the drawing, T₁, T₂ and T₃ are vacuum tubes, T₁ here being employed as a detector, T₂ as an intensifier, and T₃ as an amplifier or output tube, said tubes being operated in cascade. L₁ is a tuning inductance or coil which may be provided with taps connecting with a suitable tap switch S₁ and having connected across said coil a variable tuning condenser C₁. Antenna and ground connections are provided through fixed condensers C₂ and C₄, respectively, C₂ being of very small capacity. A grid condenser C₃ is connected from the tuned circuit L₁, C₁ to the grid of tube T₁ and a leak resistance R₃ is provided. The plate of tube T₁ is connected through a reaction coil L₂ placed in suitable inductive relation to coil L₁ and a resistor R₁ to a positive plate current supply as the battery B₂. A suitable radio frequency bypass condenser is provided at C₆ and a very small capacity condenser may be used at C₅. The plate of tube T₁ is also connected through a radio frequency choke coil L₃ and a direct current blocking condenser C₇ to the grid of tube T₂, a grid resistance for tube T₂ being indicated at R₄. A by-pass condenser C₈ is connected from choke L₃ to the tube filament circuit and serves to by-pass or attenuate radio frequency currents that otherwise may pass through choke L₃ into the audio amplifier tubes. The plate of tube T₂ is connected through a plate resistance R₂ to the plate battery B₂ and also is connected through a blocking condenser C₉ to the grid of tube T₃ for which grid resistance R₅ is provided. Condenser C₉ of small capacity is used as a by-pass across the plate of tube T₂. The plate of tube T₃ is connected through a suitable output device or loudspeaker (not shown) to the plate battery B₂ and a condenser C₁₀ of suitable ca-

pacity may be connected across the output circuit. A suitable battery B₁ or other means may be used for heating the filaments of tubes T₁, T₂ and T₃.

Particular features of my invention that distinguish it from what is known in the art appear in the use of circuit elements of unusual values which, in conjunction with the coil design and coupling and the circuits employed, produce results differing in marked degree from those ordinarily expected. All tubes are operated with below normal or rated filament voltage, or relatively low operating temperature, plate resistor R₁ is of unusual high value being variable with a maximum value of ten megohms, plate resistor R₂ is of a maximum value of three megohms, grid resistors R₃ and R₅ are of relatively high value being of the order of two to ten megohms and resistor R₄ is of high value of the order of ten megohms. These high plate resistor values are used in conjunction with a plate supply voltage of relatively low value such as eighteen to forty-five volts. Operation and performance of tube T₃ may be substantially conventional; unusual performance being obtained particularly in tube T₂ and in part in tube T₁, or both together.

Capacity C₁₁ represents the grid to plate capacity of tube T₁, which capacity may be increased by a small added condenser if desired. The grid to cathode and plate to cathode capacities of tube T₁ are not separately indicated since they are in parallel with condensers C₁—C₃ and C₅ respectively. Mutual inductance between coils L₁ and L₂ is represented by the negative mutual inductance. The plate resistance of tube T₁ is represented by R_{p1}.

By reference to the equivalent diagrammatic circuit of Figure 2, important features of my invention and the marked difference with conventional practice may be explained. Conventional circuits such as regenerative, super-regenerative and oscillating, as used in radio receiving sets, super-heterodynes, transmitters and the like employing vacuum tubes, may all be analyzed as coupled circuits in which well known principles and conditions are commonly employed: in my invention, however, such widely different conditions are employed as to result in an entirely new and different performance. Upon analysis of the circuit of Figure 2, it will be observed that three separate inductance and capacity circuits having associated series and parallel resistance are coupled together, and it is quite well understood that performance of such circuits depends

upon resistance and coupling values as well as the natural frequency response of the individual inductance and capacity circuits. Conventional practice employing tubes operated under normal 5 conditions where the plate resistance R_p is relatively low requires that relatively small coupling be employed between coils L_1 and L_2 in order that not too much damping effect be introduced into the main tuning circuit L_1-C_1 ; that is, the 10 damping effect of low plate resistance R_p or other parallel resistance of the plate circuit $L_2-C_5-C_6$ must be kept at a satisfactory low value in the tuned circuit L_1-C_1 by using relatively loose coupling if circuit operation is to be 15 satisfactory. But, upon considering the coupled circuits with regard to their individual frequencies of response, particularly the tuned circuit formed by L_1-C_1 and that formed by L_1-C_1 (parallel connected) in series with L_2 and C_1 , 20 these two circuits may have rather close natural frequencies of response when C_1 is relatively small, and the coupled circuit so formed will have two frequencies of response relatively close together when coupling between L_1 and L_2 is 25 small. By employing close coupling between coils L_1 and L_2 and keeping parallel circuit resistances relatively high in value, I avoid the damping effects and coupled circuit effects that 30 would otherwise result in broad tuning and unsatisfactory performance.

It may be seen then that my approach toward obtaining satisfactory circuit performance is completely different from that employed in conventional practice. My plan is to start with a 35 circuit designed to have suitable circuit characteristics avoiding undesired coupled circuit effects and keep out damping effects by keeping tube and other parallel circuit resistances relatively high, while conventional practice is to start 40 with tube or other parallel circuit resistances of relatively low or normal values and keep coupling effects sufficiently small to avoid excessive damping effects. In operation, my arrangement gives unusual and unexpected performance with 45 the reasons for said performance being explained or suggested above. Coupled circuits, it will be understood, are quite difficult to explain and analyze completely, but some of the differences between my practice and conventional practice are 50 believed to be clearly indicated. Practical tests have shown that my circuit may be operated, if desired, as a super-regenerative receiver without showing the broadness of tuning commonly associated with reception with this type of receiver. 55 Also, the hiss and background whistle commonly associated with the super-regenerative type of receiver are greatly reduced in intensity or eliminated by the use of my circuit arrangements.

It will be understood, of course, that I do not 60 restrict the principles herein employed and described to any one particular type of radio receiver, transmitter or the like. In the elimination of hiss and other undesirable features, my circuit features may be employed to advantage 65 in oscillators, super-heterodyne receivers and elsewhere.

Also, it will be understood that I do not limit the 70 use of my principles to any particular type of tube or method of supplying operating voltages for same. Vacuum tube characteristics have been extensively investigated for what has been considered normal operating ranges, but comparatively little data appears to be available on the tube characteristics where the operating currents are 75 extremely small. It is known, however, that the

alternating current plate resistance (R_p) of a tube increases as the applied plate potential is decreased. In some triodes, the A. C. plate resistance (R_p) may be approximately one-quarter of the computed direct current resistance at normal operating conditions; and, by this approximation, since I have operated tubes successfully with a plate current of one micro-ampere or less, the indicated A. C. plate resistance (R_p) may exceed one megohm though the same tube may 10 have a rated A. C. plate resistance (R_p) of about 10,000 ohms under normal operating conditions. It would seem, then, that successful operation of a tube with such extremely small plate current definitely proves a new and unexpected class of performance. In the amplification or "mu" of a tube is materially affected by this operation with extremely small plate current, it may be shown that the amplification obtainable from the circuit in which the tube operates is not dependent upon the "mu" of the tube, provided that "mu" is greater than unity. Regenerative circuits, or feed-back circuits, have been extensively investigated and it is known that tube circuits may provide very great amplification or a tube will generate sustained oscillations when the feed-back voltage approaches or exceeds the input voltage. Use of a tube having a high A. C. plate resistance (R_p) at normal operating potentials, such as a tetrode or other 30 "high mu" tube, seemingly would not permit the use of satisfactory circuit coupling values because of the high amplification or "mu" of the tube unless operating conditions of said tube be materially changed from the normal. 35

In practical tests and use of radio receivers employing the principles of my invention, a remarkable freedom from the obstacles or impediment commonly known in the radio field as "interference" is noticed. This freedom from interference may be difficult to explain, but it is present and seems due in large part to the coupled circuit conditions explained hereinbefore. Where coupled circuit conditions are such as here employed, giving response only to such radio 40 frequency signals as are desired with little chance for response to additional frequencies or "parasitics", it may be understood that radio receivers employing my principles will be relatively free from noise resulting from interference or shock 45 excitation. It is known that additional response frequencies in radio oscillators and transmitters give rise to "parasitics" and in receivers it may be believed that analogous conditions give rise to noise or other interference. 50

To sum up, then, features up my invention: I employ an amplifying tube or tubes operated under special conditions giving unusual and unfamiliar performance; I eliminate or greatly reduce the damping effects on inductance and 60 capacity circuits associated with said tube or tubes by tube plate circuit resistance and other circuit resistances at exceptionally high value relative to normal or usual values; and I employ a coupled circuit providing controlled feed-back, 65 regeneration or intensification, and eliminate or reduce in said coupled circuit undesirable coupled circuit effects by suitable coupling and circuit element values as explained above. 70

Having thus described my invention, what I claim is:

1. An amplifying tube and associated circuit comprising a tunable grid circuit having inductance and capacity and a plate circuit having relatively similar inductance and capacity closely 75

coupled to said grid circuit, means for reducing the damping effect to negligible value of the tube plate circuit resistance upon said closely coupled grid and plate circuits comprising the operation of said amplifying tube with a relatively high external plate circuit resistance of the order of a megohm.

2. An amplifying tube and associated circuit comprising a tunable grid circuit having inductance and capacity and a plate circuit having relatively similar inductance and capacity closely coupled to said grid circuit, means for reducing the damping effect to negligible value of the tube plate circuit resistance upon said closely coupled grid and plate circuits comprising the operation of said amplifying tube with a relatively high external plate circuit resistance of the order of a megohm and means for increasing the internal

plate resistance of said tube by operation of said tube cathode at a relatively low temperature.

3. An amplifying tube and associated circuit comprising a tunable grid circuit having inductance and capacity and a plate circuit having relatively similar inductance and capacity closely coupled to said grid circuit, means for reducing the damping effect to negligible value of the tube plate circuit resistance upon said closely coupled grid and plate circuits comprising the operation of said amplifying tube with a relatively high external plate circuit resistance of the order of a megohm and a capacity in parallel with the internal plate resistance of said tube having a reactance value greatly less than the plate resistance of said tube.
